UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,403,862.

Specification of Letters Patent. Patented Jan. 17, 1922.

Application filed October 8, 1917. Serial No. 195,357.

To all whom it may concern:

Be it known that I, ALBEN E. LUNDELL, a citizen of the United States, residing at New York, in the county of Bronx and State 5 of New York, have invented certain new and useful Improvements in Telephone-Exchange Systems, of which the following is a full, clear, concise, and exact description.

This invention relates to selective signaling, and more particularly to party line selective signaling employed in telephone systems.

Heretofore, in certain telephone systems employing machine switching, such, for instance, as that disclosed by Patent 1,218,804 issued to F. N. Reeves, March 13, 1917, the selection of ringing current for party line ringing has been determined by a special segment carried by one of the switches.

20 It is the object of this invention to improve on such a system by eliminating this special ringing segment and producing the same result by a new organization of circuits in a more efficient manner.

25 A feature of this invention is the provision of means whereby the selection of the proper source of ringing current for signaling the desired party on a party line is controlled by the registering mechanisms which are selectively operated to control the operation of 30 automatic switches in establishing a connection to the desired party line.

Other features of the invention not referred to above will more clearly appear 35 from the following description and claims.

The drawing when arranged with Fig. 2 to the right of Fig. 1, Fig. 3 below Fig. 1, Fig. 4 below Fig. 3, Fig. 6 below Fig. 4 and Fig. 5 to the right of Fig. 4, diagrammatically represents a portion of a semi-mechanical telephone system employing the present 40 invention. Only so much of the system is shown as is deemed necessary for a clear understanding of the invention.

45 The selector, connector and cordfinder switches may be of the type described in a Patent 1,123,693, to E. R. Craft and J. N. Reynolds, the cord finder switch having only one set of wipers. The sequence switches 50 may be of the type described in a Patent 1,127,808, to J. N. Reynolds and C. F. Baldwin. The all letters shown within the dotted

lines in Fig. 3 may be of the same type as the sequence switches.

It will be obvious to those skilled in the art that other types of switches and controlling apparatus of a widely varying character may be employed without departing from the spirit of the invention.

It will be assumed that a calling subscriber at an A operator's position at a distant exchange (not shown) wishes to communicate with a called substation whose line terminates at a B operator's position at the exchange shown. The A operator communicates through a well-known order wire (not shown) with the B operator and transmits to her the number of the desired line which, in the present case, will be assumed to be No. 7654. The B operator instructs the A 60 operator to extend the calling line through her cord circuit to a certain idle trunk leading to the B operator's position. Assuming that this idle trunk is the one shown in Fig. 1, the A operator inserts her plug 101 into a 65 jack 102 provided at her position in which said trunk terminates.

The B operator then depresses assignment key 103 to start a cord finder operating to connect an idle register sender to the trunk 80 assigned to the A operator. In response to the operation of key 103, a circuit is completed from grounded battery, power magnet of sequence switch 100, upper contact of sequence switch spring 104, contact of key 85 103 to ground for moving the sequence switch out of position 1 and into position 2. In position 2 of the sequence switch 100, a circuit is completed from grounded battery, winding of relay 301, lower and upper left-hand contacts of sequence switch spring 302, conductor 303, lower contacts of sequence switch spring 105, back contact and left-hand armature of relay 106 to ground. Relay 301 completes a circuit from grounded 90 battery, power magnet of sequence switch 300, lower right-hand contact of sequence switch spring 304, front contact and right-hand armature of relay 301 to ground for moving this sequence switch out of position 95 1 and into position 2. As soon as the sequence switch 300 leaves position 1, the original energizing circuit of relay 301 is opened, but this relay is maintained ener-

- gized over a circuit extending from grounded battery, winding of relay 301, lower left-hand and upper right-hand contacts of sequence switch spring 302, back contact and 5 left-hand armature of relay 305 to ground.
- In position 2 of sequence switch 300, a circuit is completed from grounded battery, winding of up-drive magnet 306, contact of sequence switch spring 307, front contact and 10 right-hand armature of relay 301 to ground. Under the control of this magnet the brush shaft 308 of the cord finder is moved in an upward direction. As soon as the test brush 309 engages the terminal 310 individual to 15 the trunk assigned to the A operator, a circuit is completed from grounded battery, winding of relay 305, upper right-hand contact of sequence switch spring 311, brush 309, terminal 310, conductor 312, contact of sequence switch spring 107, back contact and 20 right-hand armature of relay 108, upper right-hand contact of sequence switch spring 109 to ground. Relay 305 completes a locking circuit for itself from grounded battery, 25 winding of relay 305, lower contact of sequence switch spring 311, front contact and right-hand armature of relay 305, brush 375, terminal 316, conductor 317, lower right-hand and upper left-hand contacts of sequence switch spring 110, winding of relay 106, contact of sequence switch spring 111 to 30 ground. Relay 305, by attracting its left-hand armature, opens the circuit of relay 301, but this relay 301 is still maintained 35 energized until the brushes of the cord finder are accurately centered upon the terminals individual to the assigned trunk. This circuit extends from grounded battery, winding of relay 301, front contact and left-hand 40 armature of relay 301, conductor 313, conducting segment of commutator 314, commutator brush 315, to ground. As soon as the brushes are accurately centered the commutator brush 315 engages an insulating 45 segment, thereby causing the deenergization of relay 301. The retraction of the right-hand armature of relay 301 opens the circuit of the up-drive magnet 306 and closes a circuit from grounded battery, power magnet 50 of sequence switch 300, lower left-hand contact of sequence switch spring 304, back contact and right-hand armature of relay 301, to ground, for moving the sequence switch 55 out of position 2 and into position 3.
- In the meantime, the B operator has depressed the keys of her keyboard corresponding to the desired number. In response to the depression of the No. 7 thousands key, a circuit is completed from ground, upper 60 contact of the No. 7 thousands key, conductor 500, left-hand winding of relay 501, conductor 502, upper left-hand contact of sequence switch spring 318, conductor 319, upper left-hand contact of sequence switch 65 spring 320, conductor 321, lower left-hand

contact of the allotter sequence switch spring 401, winding of relay 402, lower left-hand contact of allotter sequence switch spring 403, conductor 404, upper right-hand contact of sequence switch spring 327 to grounded 70 battery. Relays 501 and 402 become energized. The relay 402 completes a locking circuit for itself from grounded battery, armature and front contact of relay 402, upper contact of allotter sequence spring 75 403, the winding of relay 402 and thence over the circuit previously described, to ground. A circuit is also completed by the depression of No. 7 thousands key from ground, lower contact of No. 7 thousands 80 key, conductor 503, left-hand winding of relay 504, lower right-hand contact of sequence switch spring 318 to grounded battery, over the circuit previously described. Relay 504 becomes energized. 85

In response to the depression of the No. 6 hundreds key, a circuit is completed from ground, upper contact of this key, conductor 505, left-hand winding of relay 506, conductor 507, lower left-hand contact of sequence switch spring 360 to grounded battery at armature and front contact of relay 402 over the circuit previously described. Relay 506 becomes energized. A circuit is also completed from ground, lower contact 90 of the No. 6 hundreds key, conductor 547, right-hand winding of relay 508, lower left-hand contact of sequence switch 318 to grounded battery over the circuit previously described. Relay 508 becomes energized 100 and completes a circuit from grounded battery through its inner armature and front contact, winding of relay 528 to ground, whereupon this relay 528 also becomes energized. 105

In response to the depression of the No. 5 tens key, a circuit is completed from ground through this key, conductor 509, left-hand winding of relay 510, upper left-hand contact of sequence switch spring 361 to 110 grounded battery over the circuit previously described. Relay 510 becomes energized.

In response to the depression of the No. 4 units key, a circuit is completed from ground through this key, conductor 512, left-hand 115 winding of relay 513, conductor 514, upper right-hand contact of sequence switch spring 362 to grounded battery over the circuit previously described. Relay 513 becomes energized.

As soon as the relays 510 and 513 become energized and attract their armatures, a locking circuit for these relays is completed from grounded battery, conductor 516, right-hand winding and right-hand armature and front contact of relay 510, conductors 517, 518 and 519, right-hand winding and right-hand armature and front contact of relay 513, conductor 520, winding 125 of relay 324, lower contact of sequence 130

switch spring 325 to ground. Relay 324 becomes energized. A locking circuit for relays 501, 506 and 508 is then completed from grounded battery, left-hand winding of relay 508, conductor 521, right-hand winding and right-hand armature and front contact of relay 501, conductor 522, right-hand winding of relay 504 (this relay being energized so that the shunt circuit around this winding is open), conductor 523, right-hand winding and right-hand armature and front contact of relay 506, conductor 524, winding of relay 326, armature and front contact of relay 324 to ground. As soon as the relay 326 becomes energized, a circuit is completed from grounded battery, power magnet sequence switch 300, armature and front contact of relay 326, contacts of sequence switch spring 325 to ground, for moving the sequence switch out of position 3 and into position 4.

When sequence switch 300 reaches position 4 a circuit is closed from grounded battery, lower contact of sequence switch spring 327, conductors 345, 346, windings of magnets 532, 533, 534, 535 in parallel to ground. These magnets, upon energization, release the depressed keys, the relays that were originally energized through contacts of these keys being held up through the above traced locking circuits with the exception of relay 402, which becomes deenergized. The deenergization of relay 402, completes a circuit from grounded battery, winding of power magnet sequence switch 300, upper contact of sequence switch spring 329, left-hand armature and back contact of relay 402, upper right-hand contact of sequence switch spring 405 to ground, for moving the sequence switch 300 out of position 4 and into position 5. A circuit is now completed from grounded battery, power magnet of sequence switch 400, contact of sequence switch spring 328, lower left-hand contact of sequence switch spring 405 to ground, for moving the sequence switch out of position 1 and into position 2. In this position of the allotter the sequence switch associated with another cord finder is moved into position 1 in a manner to be herein-after described. In position 2 of sequence switch 400, relay 402 is energized over a circuit extending from ground, lower right-hand contact of sequence switch spring 405, resistance 411, winding of relay 402, lower right-hand contact of sequence switch spring 403 to grounded battery. Through the attraction of its right-hand armature relay 402 maintains full potential on conductor 346 through the contact of sequence switch spring 412 until another cord finder has been allotted. As will hereinafter appear, when a cord finder completes its task and moves into position 18 it rests there until the one preceding it in order has been taken for use. In the present case the cord finder shown in Fig. 3 precedes another whose conductor 361, which corresponds to conductor 360 of the present case, is connected to the sequence switch spring 405 in position 70 4. When therefore the present cord finder goes into use and in the manner described the sequence switch 400 is moved into position 2, a circuit will be closed from ground, contact of sequence switch spring 362 which 75 belongs to the next cord finder, contact of sequence switch spring 410, motor magnet 400 to grounded battery. Sequence switch 400 moves into position 4, where the next cord finder is then allotted. 80

In positions 2 and 5 of sequence switches 100 and 300 respectively, a fundamental circuit is closed from grounded battery, winding of relay 113, lower and upper right-hand contacts of sequence switch spring 114, conductor 115, terminal 330, brush 331, conductor 332, contact of sequence switch spring 333, resistance 334, winding of relay 335, conductor 336, armature and back contact of counting relay 0' to ground. Relay 113 90 becomes energized and completes a locking circuit for itself through its left-hand armature and front contact and the lower left-hand contact of sequence switch spring 114. Relay 335 closes a circuit from grounded 95 battery, winding of counting relay 3, armature and back contact of counting relay 3', conductor 526, left-hand armature and front contact of relay 501, conductor 340, upper contact of sequence switch spring 339, 100 upper right-hand contact of sequence switch spring 338, armature and front contact of relay 335, to ground. Counting relay 3 closes a locking circuit for itself from grounded battery, through its winding, 105 winding of counting relay 3', armature and front contact of counting relay 3, conductor 342, contact of sequence switch spring 343 to ground. Relay 3' does not become energized at this time due to the shunt around 110 its winding through the front contacts of relays 501 and 335.

The energization of relay 113 closes a circuit from grounded battery, power magnet of sequence switch 100, upper contacts of 115 sequence switch spring 116, right-arm armature and front contact of relay 113 to ground, for driving the sequence switch 100 out of position 2 and into position 3.

In positions 3 to 13 of sequence switch 120 100 a circuit is closed from grounded battery, lamp 117, lower right-hand and upper left-hand contacts of sequence switch spring 118, interrupter 119 to ground. The flashing of the lamp 117 indicates to the B operator that the sender is connected to the assigned trunk. 125

The energization of relay 113 also closes a circuit from grounded battery, winding of up-drive magnet 120, lower and upper 130

left-hand contacts of sequence switch spring 121, right-hand armature and front contact of relay 113 to ground. Under the control of the up-drive magnet 120, the wipers and brushes carried by the rod 121 are elevated. As soon as the commutator brush 122 engages a conducting portion of the commutator segment 123, a shunt circuit is closed around the winding of relay 335, from 10 grounded battery, winding of relay 113, left-hand armature and front contact of relay 113, lower left-hand contact of sequence switch spring 114, upper left-hand contact of sequence switch spring 124, conductor 15 175, conducting segment of commutator 123, brush 122, conductor 125, upper left-hand contact of sequence switch spring 126 to ground. This shunt circuit causes the deenergization of relay 335, whereupon the relay 20 3' energizes in series with relay 3 over the circuit previously described. The energization of relay 3' extends the conductor 526 through the armature and back contact of relay 2', through the winding of relay 2 to grounded 25 battery. As soon as the brush 122 engages the first insulating segment of the selector 123, the above traced shunt path for the relay 335 is opened, whereupon the relay 335 is again permitted to attract its armature. The circuit of relay 2 is now completed, and this relay upon energization 30 closes a locking circuit for itself from grounded battery, winding of relay 2, winding of relay 2', armature and front contact of relay 2, conductor 342, contact of sequence switch spring 343 to ground. The relay 2' is permitted to energize as soon as the relay 335 is deenergized, due to the brush 122 engaging the second conducting 35 segment of commutator 123. This operation continues until the brush 122 engages the fourth conducting segment, whereupon the common relay 0' is energized and opens at its back contact the fundamental circuit, 40 causing the deenergization of relays 313 and 335. The deenergization of relay 113 opens the circuit of the up-drive magnet 120, whereupon the brushes of the selector are arrested with each set of brushes in 45 operative relation to the first set of terminals in each section of the terminal bank respectively. The deenergization of relay 113 also closes a circuit from grounded battery, power magnet of sequence switch 100, lower 50 left-hand contact of sequence switch spring 127, right-hand armature and back contact of relay 113 to ground, for moving the sequence switch out of position 3 and into position 4.

55 Relay 0' also closes a circuit from grounded battery, power magnet of sequence switch 300, lower left-hand contact of sequence switch spring 329, conductor 344, armature and front contact of relay 0' to ground, for moving the sequence switch 60 300

out of position 5 and into position 7. While this sequence switch is moving from position 5 to position 7, the locking circuit of the counting relays is opened at sequence switch spring 343 so that these relays de- 70 energize.

In position 4 of sequence switch 100, a circuit is completed from grounded battery, winding of trip magnet 128, upper right-hand contact of sequence switch spring 126 75 to ground. Trip magnet 128 becomes energized and moves a tripping finger 131 opposite a catch (not shown) provided on a cam, which holds the wipers apart and out of contact with the terminal bank. 80

When the sequence switches 100 and 300 reach positions 4 and 7 respectively the fundamental circuit is again closed, causing the energization of relays 335 and 113. The energization of relay 335 closes a circuit from grounded battery, winding of counting relay 3, armature and back contact of counting relay 3', conductor 526, conductor 577, right-hand armature and front contact of relay 528, left-hand armature and front contact of relay 504, conductor 529, lower left-hand contact of sequence switch spring 339, upper right-hand contact of sequence switch spring 338, armature and front contact of relay 335, to ground. Relay 113 completes a circuit from grounded battery, power magnet of sequence switch 100, upper contacts of sequence switch spring 116, right-hand armature and front contact of relay 113, to ground, for moving the sequence switch 100 out of position 4 and into position 5. Relay 113 is held energized while the sequence switch 100 is moving from position 4 to position 5, by a locking circuit through its left-hand armature and front contact and the lower left-hand contact of sequence switch spring 114. 95

In position 5 of the sequence switch 100 the circuit of the up-drive magnet 120 is again closed, and this magnet causes the 100 further upward travel of the brush rod 121. Upon the initial movement of this brush rod the trip finger 131 causes the removal of the cam from between the wipers of the fourth set of brushes of the selector. At the 115 same time a brush 129 engages a conducting segment of a commutator 130 and closes a shunt circuit around the winding of relay 335 from grounded battery, winding of relay 113, left-hand armature and front contact of relay 113, lower right-hand contact of sequence switch spring 114, upper right-hand contact of sequence switch spring 124, conductor 181, conducting segment of commutator 130, brush 129, conductor 125, upper 125 left-hand contact of sequence switch spring 126 to ground. The stepping relay 335 becomes deenergized and permits the energization of relay 3'. As soon as the brush 129 engages an insulated segment of the com- 130

mutator, the shunt circuit is opened and the relay 335 is again energized. During the successive engagement of the brush 129 with the commutator 130, the stepping relay 335 is operated to cause the actuation of the counting relays in the above described manner until the 0' relay is energized. The fundamental circuit is then opened and the relays 113 and 335 deenergized. The relay 113 is, however, held energized until the brushes are properly centered on the first set of terminals of the selective group, which in the present case is the fourth group, by a circuit from grounded battery, winding of relay 113, left-hand armature and front contact of relay 113, lower left-hand contact of sequence switch spring 114, upper right-hand contact of sequence switch spring 124, conductor 181, conducting portion of commutator 130, brush 129, conductor 125, upper left-hand contact of sequence switch spring 126, to ground. As soon as the brushes are properly centered, this circuit is opened and relay 113 deenergized, whereupon the circuit of the up-drive magnet 120 is opened. A circuit is also completed from grounded battery, power magnet of sequence switch 100, lower left-hand contact of sequence switch spring 127, right-hand armature and back contact of relay 113 to ground, moving the sequence switch into position 6.

The energization of counting relay 0' also completed a circuit from grounded battery, winding of power magnet 300, lower left-hand contact of sequence switch 329, conductor 344, armature and front contact of counting relay 0' to ground, for moving sequence switch out of position 7 and into position 9. While sequence switch 300 is moving from position 7 to position 9 the locking circuit of the counting relays is opened at the contact of sequence switch spring 343.

In position 6 of the sequence switch 100 a circuit is closed from grounded battery, the right-hand winding of relay 108, lower contact of sequence switch spring 132, to ground. Relay 108 closes a circuit from grounded battery, power magnet 100, upper and lower left-hand contacts of sequence switch spring 116, left-hand armature and front contact of relay 108, upper left-hand contact of sequence switch spring 109 to ground, for moving sequence switch 100 out of position 6 and into position 7. If the brushes 133, 134 and 135 of the selector are in engagement with the terminal of a busy line, ground will be found upon the test terminal 136 thereof so that the relay 108 will still be energized in position 7 due to a circuit from grounded battery, left-hand winding of relay 108, lower right-hand contact of sequence switch spring 137, right-hand armature and front contact of relay 108, conductor 138, resistance 139, brush 134, terminal 136, to ground.

The energization of relay 108 in position 7 closes a circuit from grounded battery, winding of up-drive magnet 120, left-hand contacts of sequence switch spring 121, upper right-hand and lower left-hand contacts of sequence switch spring 116, left-hand armature and front contact of relay 108, upper left-hand contact of sequence switch spring 109 to ground. Under the control of the up-drive magnet 120, the brushes 133, 134 and 135 are again moved upward until they engage the terminals of an idle trunk which does not have ground connected to its test terminal. The relay 108 will then deenergize and complete a circuit from grounded battery, power magnet of sequence switch 100, lower contact of sequence switch spring 140, back contact and left-hand armature of relay 108, upper left-hand contact of sequence switch spring 109, to ground, for moving the sequence switch 100 out of position 7 and into position 8. Relay 108 will remain energized, however, until the brushes are accurately centered on the terminals of the idle trunk due to a circuit being closed from grounded battery, right-hand winding of relay 108, upper contact of sequence switch spring 132, conductor 182, conducting portion of commutator 183, brush 184, conductor 125, lower contacts of sequence switch spring 116, left-hand armature and front contact of relay 108, upper left-hand contact of sequence switch spring 109 to ground. As soon as the brushes are actually centered this circuit is opened by the brush 184 engaging an insulated portion of the commutator 183.

In position 8 ground is connected to the test terminal 136 of the selected trunk through the upper right-hand contact of sequence switch spring 109, conductor 138, resistance 139 and test brush 134.

When the sequence switch 100 reaches position 8 and the sequence switch 300 reaches position 9, the fundamental circuit is again closed, causing the energization of relays 113 and 335. The relay 113 again completes a locking circuit for itself through its left-hand armature and front contact and the lower left-hand contact of sequence switch spring 114. The energization of relay 113 also closes a circuit from grounded battery, power magnet of sequence switch 100, upper contacts of sequence switch spring 116, right-hand armature and front contact of relay 113 to ground, for moving sequence switch 100 into position 9.

As soon as the sequence switch 100 reaches position 9 a circuit is completed from grounded battery, contact of sequence switch spring 201, right-hand winding of relay 202, lower left-hand contact of sequence switch spring 203, conductor 204, terminal 141, brush 133, lower right-hand and upper left-hand contacts of sequence switch spring 121, 139

- front contact and right-hand armature of relay 113 to ground. Relay 202 is energized and closes a circuit from grounded battery, winding of relay 205, lower left-hand and 5 upper right-hand contacts of sequence switch spring 206, left-hand armature and front contact of relay 202, to ground. Relay 205 closes a locking circuit for itself from grounded battery, winding of relay 205, 10 right-hand armature and front contact of relay 205, resistance 207, conductor 208, brush 134, resistance 139, conductor 138, upper right-hand contact of sequence switch spring 109, to ground. Relay 205 also closes a circuit from grounded battery, power magnet 15 of sequence switch 200, upper right-hand contact of sequence switch spring 209, left-hand armature and front contact of relay 205 to ground, for moving the sequence 20 switch 200 out of position 1 and into position 2. While sequence switch 200 is moving from position 1 to position 2, the relay 202 is held energized over a circuit from grounded battery, both windings of relay 202 in 25 series, upper contacts of sequence switch spring 210, right-hand armature and front contact of relay 202, lower right-hand contact of sequence switch spring 203 to ground over the circuit previously described.
- 30 In position 2 of sequence switch 200 a circuit is closed from grounded battery, winding of up-drive magnet 211, conductor 212, left-hand contacts of sequence switch 210, right-hand armature and front contact of 35 relay 202, lower right-hand contact of sequence switch spring 203 to ground over the circuit previously described. Under the control of the up-drive magnet 211 the brush rod 213 is elevated.
- 40 The energization of relay 335, due to the fundamental circuit being closed, completed a circuit from grounded battery, winding of the counting relay 1, armature and back contact of counting relay 1', conductor 530, left-hand armature and front contact of relay 506, conductor 531, lower right-hand contact of sequence switch spring 339, upper right-hand contact of sequence switch spring 338, armature and front contact of relay 335 45 to ground. Counting relay 1 completes a locking circuit for itself through the winding of counting relay 1', armature and front contact of counting relay 1, to ground, over conductor 342. The counting relay 1' is not energized at this time, due to the shunt 50 around its winding through the front contacts of relays 506 and 335.
- 55 As soon as the commutator brush 214 engages the conducting segment of the commutator 215, a circuit is closed from grounded battery, winding of relay 113, left-hand armature and front contact of relay 113, lower and upper left-hand contacts of sequence switch spring 114, conductor 143, brush 135, terminal 144, conductor 145, left-hand contact of sequence switch spring 217, conductor 218, upper right-hand contact of sequence switch spring 219, conducting segment of commutator 215, brush 214 to ground. Due to the closure of this shunt 60 path, the relay 335 becomes deenergized and permits the energization of the counting relay 1'. As soon as the commutator brush 214 engages the first insulating segment of the commutator 215, the above traced shunt 65 path is opened and the relay 335 is again energized, whereupon the counting relay 0 becomes energized. The connector continues to move upward until the brush 214 engages the second conducting segment of the 70 commutator 215, at which time the deenergization of relay 335 permits the energization 75 of the counting relay 0'. The fundamental circuit is then opened and relays 335 and 113 become deenergized. The energization 80 of counting relay 0' also closes a circuit from grounded battery, power magnet of sequence switch 300, lower left-hand contact of sequence switch spring 329, conductor 344, armature and front contact of counting relay 0' to ground, moving the sequence switch 300 out of position 9 and into position 11, 85 whereupon the locking circuit of the counting relay is opened.
- 90 The deenergization of relay 113 opens the 95 circuits of relay 202 and magnet 211. The deenergization of relay 113 also closes a circuit from grounded battery, power magnet of sequence switch 100, lower left-hand contact of sequence switch spring 127, right-hand armature and back contact of relay 113 to ground, for moving the sequence switch 100 out of position 9 and into position 10.
- 95 The deenergization of relay 202 closes a 100 circuit from grounded battery, power magnet, sequence switch 200, lower right-hand and upper left-hand contacts of sequence switch spring 206, left-hand armature and back contact of relay 202 to ground, for moving the sequence switch 105 out of position 2 and into position 3.
- 100 With sequence switches 100 and 300 in positions 10 and 11 respectively, the fundamental circuit is again closed and relays 113 and 335 become energized. The energization 115 of relay 113 closes the above traced circuit for moving the sequence switch 100 out of position 10 and into position 11 and for energizing relay 202.
- 110 The energization of relay 202 closes a circuit from grounded battery, power magnet 115 of sequence switch 200, lower and upper right-hand contacts of sequence switch 206, left-hand armature and front contact of relay 202 to ground, for moving the sequence 120 switch into position 4, whereupon the circuit for updrive magnet 211 will again be established through the lower and upper left-hand contacts of sequence switch spring 210. When the sequence switch 200 reached position 130

tion 3, a circuit was closed from grounded battery, winding of trip magnet 220, contact of sequence switch spring 221 to ground. This magnet moves a trip finger 222 into a 5 position such that upon the next upward movement of the brush rod 213, a set of brushes may be tripped.

The energization of relay 335 due to the closure of the fundamental circuit completes 10 a circuit from grounded battery, winding of counting relay 5, armature and back contact of counting relay 5', conductor 536, left-hand armature and front contact of relay 510, conductor 537, lower left-hand and upper 15 right-hand contacts of sequence switch spring 338, armature and front contact of relay 335 to ground. Counting relay 5 becomes energized and prepares a circuit for counting relay 5'. As soon as the brush 224 20 engages a conducting segment of commutator 225, ground is connected to the conductor 218, and stepping relay 335 is shunted out and permits the energization of counting relay 5' in the same manner as above described. 25 When the brush 224 engages the first insulating segment of the commutator 225, the stepping relay 335 is again energized, whereupon the relay 4 is energized. The operation of the counting relays under the control of 30 the stepping relay 335 continues until in response to the sixth engagement of the brush 224 with a conductive segment of the commutator 225, the counting relay 0' becomes energized and opens the fundamental circuit, 35 thereby causing the deenergization of relays 113 and 335. The energization of counting relay 0' also closes a circuit previously described, for moving the sequence switch 300 out of position 11 and into position 13. 40 The deenergization of relay 113 opens the circuits of relay 202 and magnet 211 and also completes a circuit from grounded battery, power magnet of sequence switch 100, lower left-hand contact of sequence switch spring 45 127, right-hand armature and back contact of relay 113 to ground, for moving the sequence switch into position 12. The deenergization of relay 202 completes the circuit previously described for moving the sequence 50 switch 200 out of position 4 and into position 5. The magnet 220 becomes deenergized as soon as the sequence switch 200 leaves position 4.

When the sequence switches 100 and 300 55 reach positions 12 and 13 respectively, the fundamental circuit is again closed, whereupon the relays 113 and 335 become energized. Relay 113 again closes a circuit through the upper contacts of sequence 60 switch spring 116 for moving the sequence switch 100 out of position 12 and into position 13. This relay also closes a circuit for causing the energization of relay 202, which by attracting its left-hand armature completes a circuit from sequence switch 200, for

moving the sequence switch out of position 5 and into position 6.

In position 6 of the sequence switch 200, a circuit is closed from grounded battery, winding of up-drive magnet 226, conductor 70 227, lower right-hand and upper left-hand contact of sequence switch 210 and then to ground at the right-hand armature and front contact of relay 113. Under the control of magnet 226, the brush rod 213 is elevated at 75 a slower rate of speed than under the control of the up-drive magnet 211.

Upon the energization of relay 335, when the fundamental circuit was closed, a circuit was completed from grounded battery, 80 winding of counting relay 4, armature and back contact of counting relay 4', conductor 538, left-hand armature and front contact of relay 513, conductor 539, upper contacts of sequence switch spring 338, armature and 85 front contact of relay 335 to ground. Counting relay 4 becomes energized and prepares a circuit for counting relay 4'.

As the brush rod 213 is elevated under the control of magnet 226, the brush 214 again 90 connects ground through the commutator 215, upper right-hand contact of sequence switch spring 219, conductor 218, lower left-hand contact of sequence switch spring 217, conductor 145 to the winding of relay 113, 95 causing thus the deenergization of relay 335. As soon as this shunt circuit has been closed five times, the counting relay 0' is again energized, whereupon the fundamental circuit is opened and the relays 113 and 335 100 become deenergized. The counting relay 0' closes the previously described circuit for sequence switch 300, for moving it out of position 13 and into position 16. The deenergization of relay 113 opens the circuits of relay 202 and magnet 226, and also completes a circuit through the lower left-hand contact of sequence switch spring 127 for moving the sequence switch 100 out of position 13 105 and into position 14. The deenergization of relay 202 completes a circuit from grounded battery, power magnet of sequence switch 200, lower right-hand and upper left-hand contacts of sequence switch spring 206, left-hand armature and back contact of relay 202 110 to ground, for moving the sequence switch 200 out of position 6 and into position 7.

As soon as the sequence switches 100 and 200 reach positions 14 and 7 respectively, a circuit is completed from grounded battery, 120 upper contact of sequence switch spring 201, right-hand winding of relay 202, lower left-hand contact of sequence switch spring 203, conductor 204, terminal 141, brush 133, lower and upper right-hand contacts of sequence switch spring 121, conductor 147, upper armature and back contact of relay 148, upper right-hand winding of repeating coil 149 to ground. Relay 202 completes a circuit from grounded battery, power mag- 125 130

net sequence switch 200, lower and upper right-hand contacts of sequence switch spring 206, left-hand armature and front contact of relay 202 to ground, for moving 5 the sequence switch out of position 7 and into position 8.

It will first be assumed that the called line is idle and full battery potential is connected to the test terminal 230. A circuit is then 10 completed from grounded battery through the cut-off relay 231 of the called line, terminal 230, brushes 232, conductor 233, lower right-hand contact of sequence switch spring 234, left-hand winding of relay 235, 15 lower contacts of sequence switch spring 236, right-hand winding of relay 235 to ground. Relay 235 becomes energized and closes a locking circuit for itself through its left-hand low resistance winding and its 20 left-hand armature and front contact to ground at the left-hand armature and back contact of relay 237. Due to the closure of this circuit, the potential at the test terminal 230 and multiples thereof is reduced so as to 25 prevent the seizure of this line by another selector switch. The energization of relay 235 also completes a circuit from grounded battery, power magnet of sequence switch 200, lower left-hand contact of sequence 30 switch spring 209, conductor 238, right-hand armature and front contact of relay 235, right-hand armature and back contact of relay 237 to ground, for moving the sequence switch out of position 8 and into position 35 10. This sequence switch is immediately moved out of position 10 into position 14 by a circuit from grounded battery, power magnet of sequence switch 200, lower right-hand and upper left-hand contact of sequence 40 switch spring 206, left-hand armature and back contact of relay 202 to ground. Relay 202 was deenergized due to its circuit being opened at the lower left-hand contact of sequence switch spring 203, when the sequence 45 switch 200 leaves position 7 $\frac{1}{4}$. Sequence switch 200 is immediately moved out of position 14 into position 16, due to the circuit previously described for moving it out of position 8.

50 When the sequence switch 100 reaches position 14, a circuit is completed from grounded battery, lamp 150, upper right-hand and lower left-hand contacts of sequence switch 118 to ground. The steady lighting 55 of the lamp 150 indicates to the B operator that connection has been established to the called party and that the apparatus is now in condition for ringing the called party. The B operator then depresses the ringing key 60 151, which completes a circuit from grounded battery, winding of relay 152, closed contact of ringing key 151 to ground. Relay 152 closes a circuit from grounded battery, power magnet of sequence switch 100, lower left-hand contact of sequence switch spring 65

104, armature and front contact of relay 152, contact of sequence switch spring 111 to ground, for moving the sequence switch out of position 14 and into position 15. The sequence switch 100 is immediately moved out of position 15 due to a circuit being closed from grounded battery, power magnet of sequence switch 100, upper left-hand contact of sequence switch spring 127, conductor 175, upper left-hand and lower contacts of sequence switch spring 124 to ground. The sequence switch is stopped in either position 16 or position 17, depending upon the condition of relay 108.

Under the conditions assumed, when the sequence switch 100 reaches position 12, a circuit is completed from grounded battery, left-hand winding of relay 108, upper right-hand contact of sequence switch spring 137, conductor 154, terminal 348, brush 349, conductor 350, outer left-hand armature and front contact of relay 508 to ground. This circuit is maintained closed until the sequence switch 100 leaves position 16 $\frac{1}{2}$. Relay 108 by attracting its right-hand armature extends the holding circuit of relay 305 through conductors 317 and 155, lower contact of sequence switch spring 156, right-hand armature and front contact of relay 108, upper right-hand contact of sequence 90 switch spring 109 to ground. Relay 108 also closes a circuit for sequence switch 100 as soon as it reaches position 16, from ground battery, upper contact of sequence switch spring 140, right-hand armature and front contact of relay 108, upper right-hand contact of sequence switch spring 109 to ground, for moving the sequence switch into position 17. As soon as the sequence switch 100 leaves position 16 $\frac{1}{2}$, the energizing circuit of relay 108 is opened, thereby causing the deenergization of relay 108, which in turn opens the holding circuit of relay 305. The deenergization of relay 305 completes a circuit from grounded battery, power magnet of sequence switch 300, upper contact of sequence switch spring 304, left-hand armature and back contact of relay 305 to ground, for moving the sequence switch out of position 105 110 and into position 17. A circuit is now closed from grounded battery, winding of down-drive magnet 352, conductor 353, lower and upper right-hand contacts of sequence switch spring 302, left-hand armature and back contact of relay 305 to ground. Under the control of the down-drive magnet 352, the brush shaft 308 is returned to its 120 normal position. As soon as the normal position is reached, the brush 315 engages the normal conducting segment 354 and a circuit is completed from grounded battery, power magnet of sequence switch 300, upper right-hand contact of sequence switch spring 355, conducting segment 354, brush 315 to ground, for moving the sequence switch out 125 130

of position 17 and into position 18, whereupon the circuit of down-drive magnet 352 is opened.

- As soon as the power magnet of sequence 5 switch 400 is moved into position 17, a circuit is closed from grounded battery, power magnet of sequence switch 400, contacts of sequence switch spring 410, contact of sequence switch spring 357 to ground, for 10 moving the sequence switch 400 into position 1. A circuit is thereupon closed from grounded battery, power magnet of sequence switch 300, lower right-hand contact of sequence switch spring 329, lower left-hand 15 contact of sequence switch spring 405 to ground. This circuit causes the sequence switch to move out of position 18 and into position 1, thereby allotting this cord finder for service.
- 20 When the relay 108 became deenergized in position 16½ of sequence switch 100, a circuit was completed from grounded battery, lower left-hand and upper right-hand contacts of sequence switch spring 110, back 25 contact and left-hand armature of relay 108, conductor 158, armature and back contact of marginal relay 159, armature and back contact of relay 160, winding of ringing relay 148, conductors 161 and 162, upper contacts 30 of sequence switch spring 163, contacts of ringing key 151 to ground. The relay 148 becomes energized, but the relay 160 is prevented from becoming energized in series 35 with relay 148, due to a shunt around its winding through its back contact and the back contact of relay 159. Upon energization, relay 148 closes the ringing circuit which extends from a grounded source of ringing current through the right-hand 40 winding of relay 159, right-hand contact of sequence switch spring 164, lower armature and front contact of relay 148, contact of sequence switch spring 165, conductor 143, brush 135, terminal 144, conductor 145, contacts of sequence switch spring 217, brush 45 240, terminal 241, bell at substation No. 7654, terminal 242, brush 243, conductor 244, upper contact of sequence switch spring 203, conductor 204, terminal 141, brush 133, lower 50 and upper right-hand contacts of sequence switch spring 121, conductor 147, upper armature and front contact of relay 148 to ground. As soon as the called subscriber removes the receiver from the switchhook, 55 sufficient current is allowed to flow through the ringing circuit to cause the relay 159 to attract its armature. This movement of the armature of relay 159 removes the shunt from around the winding of relay 160, which 60 then becomes energized. Relay 160 by attracting its armature closes a locking circuit for itself over conductor 162 to ground through the ringing key. This locking circuit closes a shunt circuit around the winding 65 of relay 148, which becomes deenergized

and completes the talking circuit between the calling and called party. As soon as the relay 148 deenergizes, a supervisory relay 166 becomes energized and completes a circuit for the supervisory relay 167. The 70 supervisory relay 167 becomes energized and connects ground to conductor 162 for maintaining the relay 160 energized after the operator releases the ringing key 151.

When disconnection is desired and the 75 called subscriber restores his receiver to the switchhook, the relay 166 becomes deenergized and opens the circuit of relay 167. Relay 167 opens the circuit of relay 160 and also actuates a well-known supervisory signal 80 at the A operator's position. The A operator after receiving the signal from the called subscriber removes the plug 101 from the jack 102. The deenergization of relay 167 opens the circuit of relay 152, which deenergizes and closes a circuit from grounded battery, lower and upper left-hand contacts of sequence switch spring 110, winding of relay 106, armature and back contact of relay 152, brush 167, interrupter 168 to 85 ground. When the interrupter 168 closes its circuit, relay 106 becomes energized and closes a locking circuit for itself through its left-hand armature and front contact. Relay 106 also closes a circuit from grounded 90 battery, winding of relay 113, conductor 170, upper contacts of sequence switch spring 105, right-hand armature and front contact of relay 106, brush 169, interrupter 168, to 95 ground. As soon as the interrupter 168 100 closes this circuit, relay 113 energizes and closes a circuit from grounded battery, power magnet of sequence switch 100, upper contacts of sequence switch spring 116, right-hand armature and front contact of 105 relay 113 to ground, for moving the sequence switch into position 18. In position 18 a circuit is closed from grounded battery, winding of down-drive magnet 172, lower contact of sequence switch spring 126 110 to ground, for returning the brush rod to normal. As soon as the brush rod reaches its normal position, a circuit is closed from grounded battery, power magnet of sequence switch 100, lower right-hand contact of sequence switch spring 127, normal conducting segment 175, brush 129, conductor 125, upper left-hand contact of sequence switch 126 to ground, for moving the sequence switch into position 1, whereupon the circuit of the down-drive magnet 172 is opened.

As soon as the sequence switch 100 leaves position 17, the circuit of relay 205 is opened at the upper right-hand contact of sequence switch spring 109. This relay becomes 125 deenergized and closes a circuit from grounded battery, power magnet of sequence switch 200, upper left-hand contact of sequence switch spring 209, left-hand armature and back contact of relay 205 to ground, for 130

moving the sequence switch 200 out of position 16 and into position 18. In position 18, a circuit is closed from grounded battery, winding of down-drive magnet 250, lower 5 contact of sequence switch spring 251 to ground. Under the control of the down-drive magnet 250, the brush rod of the connector switch is returned to its normal position. As soon as the brush rod reaches its 10 normal position a circuit is closed from grounded battery, power magnet of sequence switch 200, lower right-hand contact of sequence switch spring 209, conductor 252, conducting segment 253, brush 224 to 15 ground, for moving switch 200 out of position 18 and into position 1, whereupon the circuit of the down-drive magnet 250 is opened.

If the called line had been busy, the potential on the test terminal 230 and multiples thereof would have been reduced, due to the low resistance path closed through the left-hand low resistance winding of a relay similar to relay 235. In this case, upon the 20 movement of the sequence switches 100 and 200 into positions 14 and 8 respectively, the marginal relay 235 does not become energized. A circuit is closed at the connector switch from grounded battery, left-hand and 25 right-hand winding of relay 202, upper and lower left-hand contacts of sequence switch spring 254, armature and back contact of relay 255, right-hand armature and back contact of relay 235, right-hand armature 30 and back contact of relay 237 to ground, for maintaining relay 202 energized. Relay 202 closes a circuit from grounded battery, power magnet of sequence switch 200, lower and upper right-hand contacts of sequence 35 switch spring 206, left-hand armature and front contact of relay 202 to ground, for moving the sequence switch 200 out of position 8 and into position 10. Relay 202 is still maintained energized in position 10 due 40 to the circuit previously described. A circuit is now closed from grounded battery, winding of up-drive magnet 226, conductor 227, lower right-hand and upper left-hand contacts of sequence switch spring 210, right-hand armature and front contact of relay 202, contact 257, lower and upper left-hand contacts of sequence switch spring 258 to ground. Under the control of the up-drive 45 magnet 226, the brush shaft 213 moves upward until the brush 224 engages the overflow contact 259. A circuit is then closed from grounded battery, power magnet of sequence switch 200, lower contact of sequence switch spring 260, conductor 261, overflow contact 259, brush 224 to ground, 50 for moving the sequence switch 200 out of position 10 and into position 14. In position 14, a circuit is closed from grounded battery, winding of down-drive magnet 250, upper 55 contact of sequence switch spring 251, right-

hand armature and back contact of relay 235, right-hand armature and back contact of relay 237, to ground, for returning the brush rod 213 to its normal position. As soon as the normal position is reached, a 60 circuit is completed from grounded battery, power magnet of sequence switch 200, lower right-hand contact of sequence switch 209, conductor 252, normal contact 253, brush 224 to ground, for moving the sequence 65 switch 200 out of position 14 through position 16 to position 17. As soon as the B operator depresses her ringing key and sequence switch 100 moves in position 17, a circuit is closed from ground, resistance 262, 70 interrupter 263, upper contacts of sequence switch spring 236, conductor 145, terminal 144, brush 135, conductor 143, contact of sequence switch spring 165, lower armature and front contact of relay 148, right-hand 75 winding of relay 159 to grounded source of ringing current. Relay 159 becomes energized and causes the energization of relay 160 and the deenergization of relay 148 in the manner above described. The circuit of 80 the interrupter 263 is then extended through the lower armature and back contact of relay 148, winding of supervisory relay 166, lower right-hand winding of repeating coil 149 to grounded battery. Relay 166 is inter- 85 mittently energized and deenergized under the control of the interrupter 263 and causes the vibration of the armature of relay 166. The vibration of this armature of relay 166 results in the flash of a signal in the A 90 operator's position, whereupon this operator removes plug 101 from jack 102. Relay 167 then remains deenergized and causes the release of the selector switch in the same manner as above described. As soon as test 95 brush 134 of the selector switch leaves the test terminal 136, relay 205 becomes deenergized and completes a circuit for moving the sequence switch out of position 17, whereupon this sequence switch is returned 100 to its normal position in the same manner as above described.

It will now be assumed that the number of the desired called substation is No. 7454 and is on the same party line with substation 115 No. 7654. The B operator will now depress the No. 7 thousands key, the No. 1 hundreds key, the No. 5 tens key and the No. 4 units key. The depression of these keys will result in the energization of relays 501, 504, 120 506, 510 and 513 in the same manner as above described. But the depression of the No. 1 hundreds key does not cause the energization of relays 508 and 528 as did the depression of the No. 6 hundreds key. The 125 operation of the selector and connector switches under the control of the register relays will be the same as above described except that a trunk in the first group of contacts served by the fourth set of brushes will 130

be selected. This selection is determined in position 7 of sequence switch 300 by the following circuit; grounded battery, winding of counting relay 2, conductors 600 and 601, 5 right-hand armature and back contact of relay 528, left-hand armature and front contact of relay 504, conductor 529, lower left-hand contact of sequence switch spring 337 to ground at the armature and front contact 10 of relay 335.

It is not believed that a complete description of the operation of establishing a connection to the called line No. 7154 is necessary, as it will be obvious from the above description how the sender will control the switches to establish a connection to the terminals 263, 264 and 265 of this line.

When the sequence switch 100 moves from position 13 into 14 after the last series of 20 impulses, the holding circuit of relay 305 is opened at the lower left contact of sequence switch spring 109. This relay de-energizes at this time and causes the restoration of the cord finder, since the circuit for 25 relay 108 is not completed at the outer armature and front contact of relay 508 in positions 12 to 16 of sequence switch 100. The sequence switch 100 is moved out of positions 14 and 15 in the same manner as above 30 described, but comes to rest in position 16. Ringing current is now applied in position 16 through the left-hand winding of relay 159 instead of through the right-hand winding in position 17. This ringing current is 35 of a different characteristic and is arranged to operate the bell at substation 7154 only, whereas the ringing current through the right-hand winding is arranged to operate the bell at substation 7654 only. As soon as 40 the called party answers, relay 160 is energized, causing the deenergization of relay 148, thus connecting the lines for communication. At the close of conversation relay 113 is energized over the circuit described 45 and the selector and connector switches are returned to normal.

What is claimed is:

1. In a telephone exchange system, the combination with party lines, means including a selector and a connector switch for establishing a connection to one of said lines, a movable brush set for said selector, and means to position said brush set, of apparatus at said selector switch for applying selective signaling current to said party lines, a variably adjustable device for controlling the operation of said switches, and means associated with said device and independent of said brush positioning means for controlling the operation of said signaling apparatus.

2. In a telephone exchange system, the combination with party lines, means including a selector and a connector switch for establishing a connection to one of said lines,

a movable brush set for said selector, and means to position said brush set, of apparatus at said selector switch for applying selective signaling current to said party lines, an impulse transmitting mechanism arranged to control the operation of said switches, a variably adjustable device for controlling said impulse transmitting mechanism, and means associated with said device and independent of said brush positioning means for controlling the operation of said signaling apparatus. 70 75

3. In a telephone exchange system, the combination with party lines, means including a selector and a connector switch for establishing a connection to one of said lines, a movable brush set for said selector, and means to position said brush set, of sources of ringing current of different characteristics at said selector switch, a variably adjustable device for controlling the operation of said switches to establish a connection to a desired line, and means controlled by said device and independent of said brush positioning means for selecting the proper one 80 85 90 of said sources of ringing current for signaling the desired party on said line.

4. In a telephone exchange system, the combination with party lines, means including a selector and a connector switch for establishing a connection to one of said lines, a movable brush set for said selector, and means to position said brush set, of sources of ringing current of different characteristics at said selector switch, a variably adjustable device for controlling the operation of said switches to establish a connection to a desired line, and a relay at said selector switch operative in accordance with the adjustment of said device and independent of 95 100 105 said brush positioning means for controlling the selection of the proper source of ringing current for signaling the desired party on said line.

5. In a telephone exchange system, the combination with party lines and means including a selector and a connector switch for establishing a connection to one of said lines, of mechanism at said selector switch for applying selective signaling current to 110 115 said party lines, a controlling device comprising sets of keys and sets of register relays arranged to be selectively operated in response to the operation of such keys to control the operation of said switches, and 120 means also operated in response to the operation of said keys for controlling the operation of said signaling mechanism.

6. In a telephone exchange system, the combination with party lines, means including a selector and a connector switch for establishing a connection to one of said lines, a movable brush set for said selector, and means to position said brush set, of apparatus at said selector switch for applying 125 130

selective signaling current to said party lines, a controlling device comprising sets of keys and registering mechanisms arranged to be selectively operated in response to the 5 operation of said keys to control the operation of said switches, and means controlled by said registering mechanisms and independent of said brush positioning means for controlling the operation of said signaling apparatus.

7. In a telephone exchange system, the combination with party lines, means including a selector and a connector switch for establishing a connection to one of said lines, 15 a movable brush set for said selector, and means to position said brush set, of apparatus at said selector switch for applying selective signaling current to said party lines, a controlling device comprising sets of keys 20 and registering mechanisms arranged to be selectively operated in response to the operation of such keys to control the operation of said switch, and a relay controlled by the operation of such keys and independent 25 of said brush positioning means for controlling the operation of said signaling apparatus.

8. In a telephone exchange system, the combination with party lines, means including automatic switches for establishing 30 a connection to one of said lines, movable

brush sets for said switches, and means to position said brush sets, of apparatus for applying selective signaling current to said party lines, a controlling device comprising 35 sets of keys and registering mechanisms arranged to be selectively operated in response to the operation of said keys to control the operation of said switches, and means controlled by the condition of said mechanisms 40 as determined by the operation of said keys and independent of said brush positioning means for controlling the operation of said apparatus for applying selective signaling current to said party lines. 45

9. In a telephone exchange system, the combination with party lines and means including automatic switches for establishing a connection to one of said lines, of mechanism for applying selective signaling 50 current to said party lines, a controlling device comprising sets of keys and sets of register relays arranged to be selectively operated in response to the operation of said keys to control the operation of said switches, 55 and means also operated in response to the operation of said keys for controlling the operation of said signaling mechanism.

In witness whereof, I hereunto subscribe my name this 27th day of September, A. D. 60 1917.

ALBEN E. LUNDELL.
